HEIGHT MEASURING STICK

Edward F. Joyce 3rd, 205 Rockaway St.,
Boonton, N.J. 07005

Filed June 5, 1967, Ser. No. 7,360

Term of patent 3½ years

(Cl. D52—6)

FIGURE 1 is a front elevational view of a height measuring stick embodying my new design;

FIGURE 2 is a top plan view thereof;

FIGURE 3 is a left, side elevational view thereof;

FIGURE 4 is a right, side elevational view thereof;

FIGURE 5 is a rear elevational view thereof; and
FIGURE 6 is a cross-sectional view taken along the line 6—6 of FIGURE 1.

I claim:

The ornamental design for a height measuring stick, as shown and described.
